UNITED STATES PATENT OFFICE.

HARRY S. CORNISH, OF NEW YORK, N. Y.

LIQUID-DISPENSING APPARATUS.

No. 887,312.

Specification of Letters Patent. Patented May 12, 1908.

Application filed May 28, 1906. Serial No. 319,044.

To all whom it may concern:

Be it known that I, HARRY S. CORNISH, a citizen of the United States, and a resident of New York, in the county of New York and State of New York, (with post-office address 5 118 West Forty-first street,) have invented certain new and useful Improvements in Liquid-Dispensing Apparatus, of which the following is a specification.

10 My invention relates to apparatus for dispensing liquids such as root beer, birch beer, cream ale, etc. which, either because of the tendency to foaming due to the high pressure under which they must be vended or because 15 of the condition of high fermentation as with ale, cannot be drawn and served directly from the package, tank or receptacle in which they are stored. If the liquid be drawn directly from the tank, it is necessary 20 to wait a long time for the foam to settle so as to secure a sufficient body to form a salable drink, while on the other hand, if the liquid be drawn off into a secondary receptacle and left there for a long time so as to settle 25 into a completely solid condition, it will, if not soon used, become stale.

The object of my invention is to provide an apparatus of cheap and simple construction and capable of more ready adjustment 30 and uniform action than previous forms of apparatus designed to dispense liquid from a source of charged liquid supply in two streams by the use of a suitable double draft dispensing faucet, still liquid reservoir and 35 connections direct from the faucet to the charged liquid supply and from the still liquid reservoir on the one hand to the faucet and on the other hand to the charged liquid supply.

40 To this end my invention consists in the special combinations of apparatus herein-after more particularly described and then specified in the claims.

In the accompanying drawings, Figure 1 45 is a general vertical section and side elevation of an apparatus embodying my invention, the dispensing faucet being shown in side elevation. Fig. 2 is a vertical section of a form of float controlled valve that may be 50 used for the settling or expansion chamber. Fig. 3 is a vertical section through a form of dispensing faucet which I prefer to employ. Fig. 4 is a general plan of the same showing the relation of the various ports to the disk 55 therein and to the pipes leading through the shank of the faucet and adapted for connec-

tion with pipes leading from the settling or expansion chamber and the tank or package containing the charged liquid. Fig. 5 is a horizontal section taken on the line 1—1, 60 Fig. 1.

In the preferred form of carrying out my invention, A indicates the outer casing of the apparatus which may be of wood or any other suitable material and in the form of a 65 barrel or in any other suitable form.

B indicates an inner casing supported on the bottom of the outer casing A and separated from the main body portion of the outer casing by a closed air space surround- 70 ing the inner casing B.

C indicates the reservoir containing the liquid in a still condition supported within the upper portion of the inner casing B and separated from the inner casing by a space in 75 which the ice for cooling is stored.

P indicates a double draft dispensing faucet of any suitable character having connections direct to a storage tank or receptacle G containing the charged liquid and to the still 80 liquid reservoir C, the latter being on the other hand connected also to the charged liquid supply G through an automatic valve controlled by a float and adapted to replenish the contents of the still liquid reservoir, as 85 will be hereinafter more particularly described. The dispensing faucet P is of suitable character for dispensing liquid directly into a drinking glass or mug and may be made as hereinafter more particularly set 90 forth.

H indicates a pressure reducing and regulating valve interposed between the charged liquid supply G and a conduit which passes up through the bottom of the casing A as 95 shown, the conduit being elongated and coiled to form suitable coils E and connects with a T-joint or coupling marked F. From the latter a branch pipe or connection f is carried through the walls of the inner and 100 outer casings to the faucet and another branch or connection f' to an inlet valve I which controls the flow of the liquid from the charged liquid supply G into the still liquid reservoir C.

The coils E are preferably supported in the 105 space below the still liquid reservoir C, which constitutes a cooling chamber, by means of a platform secured to the inner casing B somewhat above the bottom of the outer casing and forming a supplementary bottom for the 110 casing B. This refrigerating chamber is in communication with the ice storage space

between the inner casing B and reservoir C so that the iced water from the ice storage space will flow into this chamber and surround the conduit D entering the chamber, 5 the coils E and its branches located therein and also envelop the lower part of the reservoir C. As iced water is a better cooling agent than ice itself, all the liquid would remain in a cold state by the use of a comparatively small amount of ice. A suitable 10 overflow drain pipe might be used as indicated at Q so that the iced water would not run off until it had reached a desired level above the liquid in the reservoir C.

15 M indicates the mouth of the valve I through which the liquid flows into the still liquid reservoir C, its flow being controlled automatically by the action of a float L. The float L is attached to the arm K by a rod 20 which may be secured in any position on said arm by means of a set screw L' to thereby vary the height to which the liquid may rise in the reservoir before the valve shall shut off the flow from the charged liquid supply G. 25 As shown, the dispensing faucet is located just below the level of the outlet from the reservoir and so that the liquid discharging from said reservoir under slight liquid head will not be caused to foam excessively in the 30 act of passing through the valve passages and outlet.

O indicates the pipe forming a still liquid outlet from the reservoir C passing preferably through the cooling chamber and through 35 the walls of the inner and outer casings and across the space between them to the dispensing faucet located outside the casing A. The outlet O makes connection with the liquid in the reservoir C preferably through the 40 bottom thereof and is of such size as to allow the liquid to flow with comparative freedom. By this construction all the liquid may be drawn from the reservoir C and without excessive foaming.

45 The preferred construction of the valve I is more clearly shown in Fig. 2. A stem *j* of the valve works in the outlet pipe M and is provided with a laterally extending pin or pins *m* for engagement by a hook or extension forming the short arm of pivoted lever K, so that when the float L falls, the stem of the valve will be lifted and liquid permitted to flow from an expansion chamber in said valve through the outlets of the valve and 55 into the still liquid reservoir C. The connection of pipe *f'* with the valve body is made at *f*².

N is a suitable adjusting or throttle valve 60 interposed in the connection from *f*² to the valve that controls the escape of liquid through the outlet into reservoir C. By means of this valve the size of the passage through which the liquid is supplied to the reservoir may be regulated to adjust or 65 vary the flow into the reservoir according

to the demand made upon the temporarily accumulated quantity of still liquid by operation of the dispensing faucet. When the liquid is drawn off more frequently from the reservoir, said valve is opened slightly 70 so that a larger stream may be supplied to the tank, but as will be obvious the pressure under which said larger stream flows will be the same as with a smaller stream, and hence there will be no increased tendency 75 to foam in the discharged stream discharging into the reservoir and no excessive foaming therein beyond the capacity of said reservoir operating as a settling tank. If on the other hand, the demand at the faucet 80 is small, the valve N may be adjusted to curtail the flow. By adjustment of the float the average amount of liquid stored temporarily in the reservoir may be regulated, so that the height of liquid therein shall 85 normally stand at a higher or lower level according to the maximum probable demand made on the contents of the reservoir by the operator. As will be seen, no practical variation of the head under which the 90 liquid is drawn from the reservoir will be introduced by these adjustments and under ordinary conditions the liquid will flow out of the reservoir without being subjected to any pressure of gas from the original supply 95 source, whereas in some previous constructions of apparatus employed for a similar purpose not only is it necessary to employ pressure upon the surface of the liquid in the tank used as a settling tank in order to 100 force it to the higher level at which the faucet is situated, but the construction necessitates also a pressure which varies with the demand and likewise varies as the level of the liquid falls nearer to the outlet 105 from said tank through which the liquid passes to the dispensing faucet.

The dispensing faucet in its preferred form comprises a disk W turning on a seat X and provided with a suitable operating 110 handle connected to the stem on which the disk is secured. The seat X is preferably made or provided with some compressible substance in which annular sealing rings on the face of the disk W will impress themselves, said annular projecting rings including between their two circumferences an annular space in which includes the several ports disposed in the circumference of a circle in the seat X. The disk W has in its 115 face ports *a'*, *a'* connected by a channel *b'* in the disk. The ports or openings *a'* are in the face thereof opposite the valve seat X and are of the same or somewhat larger size than the lower pair of ports *c'* which 120 pass through the valve seat A and with which the ports *a'* may be brought into simultaneous registry by turning the valve to proper position. One port *c'* opens into the lower chamber Y in the spout of the 125 130

faucet and the other communicates with the large pipe or passage O leading back through suitable couplings to the settling or expansion chamber C. The other pair of ports 5 e', e' , represented in dotted lines in Fig. 4, communicate, one with a small pipe Z through which a fine stream of high pressure may pass, and the other with connecting pipe f through which the liquid charged and 10 under pressure is drawn from the package or tank G.

By placing the channel b' in connection with the ports c', c' of the valve seat X, a full free stream is secured from the reservoir 15 C through the outlet pipe O passing along the shank of the faucet P. By placing the channel b in connection with the ports e', e' , a fine stream of high pressure is secured from the main supply through the branch pipe f 20 passing along the shank of the faucet P. By placing the disk channel b' with the ports a', a' at the position shown in Fig. 4 the valve is closed. By locating the ports c', c' and e', e' at the proper distance apart, 25 no stop is required for governing the disk W for at no time can the channel b', b' form a connection between the channel supply pipes and this absence of a stop greatly lengthens the wear of the faucet. This 30 faucet P is supplied with the usual adjusting sleeve and lock nut permitting a continual tightening of the valve should it leak.

The spout of the faucet is an open chamber Y, the delivery port c' for the liquid under low pressure opening directly into it to facilitate a free flow, while the delivery port e' has a very small pipe Z attached, this pipe Z extending to the bottom of the spout chamber Y, thus insuring a steady stream under 40 high pressure to be directed into the receptacle, a glass or mug.

The operation of the apparatus follows: At rest, with the apparatus empty, the ports a', a' of the disk W, of the faucet are at a 45 point where the faucet will be closed, while the reservoir C being empty, the float L is pendent in the tank C. The adjusting valve N having previously been tested and set at a point that will prevent the overflow of the 50 reservoir C by reason of an excess of foam, the apparatus is now connected to a tank—of root beer for instance, under 120 lbs. pressure, and the flow turned on. The liquid will pass through the conduit to the supply 55 fixture F where it divides one stream passing to the faucet P at a, the other to the valve I which is open and into the reservoir from whence it flows to the larger outlet pipe O. The flow through the valve is cut down by 60 the throttle valve N which permits a limited flow only, and this, in combination with the expanding chamber in the valve provides a gentle, though copious, discharge although the initial pressure is 120 lbs. When a sufficient quantity has entered the reservoir C

and has settled, the float L rises and closes the valve I. The initial test of the apparatus determines the proper point at which to set the valve N so as to permit the liquid foam to settle into solid and operate the 70 float L to close the valve I without having an excess of foam flow over the top of the reservoir C and thereby flood the reservoir. By turning the disk W so that the port a', a' connects the seat ports c', c' , these ports having 75 large diameters, a full free stream will flow from the reservoir C along the outlet pipe O to the faucet, through the ports c', c' and disk channel b', into the spout chamber Y, and thence into the serving glass. A portion of 80 the glass having been filled, the disk ports a', a' are placed in connection with the seat ports e', e' , and these latter being of very small diameter, a fine stream under high pressure will flow along the pipes to the faucet P 85 through the ports e', e' and continuing through the outlet pipe Z, will deliver a highly charged and foamy liquid directly into the liquid already in the glass, imparting to the whole drink a sparkling condition. The contents of the reservoir C being lowered, the dropping of the float L opens the valve I, replenishing the contents, and if but one drink be drawn, this inflow is very slight, as the float L is very sensitive and acts immediately. If several drinks are drawn in succession, dropping the float L quickly and considerably, a violent rush of liquid is prevented by the throttle N and even if sufficient liquid is drawn to carry off all of the solid 100 liquid from the reservoir C, the valve N will always prevent a flooding of the reservoir C until the incoming foam has changed into solid sufficient to operate the float L and close the valve J.

The reservoir C can be made large enough so that it is physically impossible to draw and serve drinks so often but there will always be solid liquid in the reservoir. If, for any reason, it may become desirable to dispense the contents so as to empty the reservoir C, the throttle valve N may be set so as to close the valve I permanently, preventing a further inflow to the reservoir C, even though the float L drops, while still affording 115 a supply to the fine stream under high pressure through the branch f. This might occur near the close of a day's business. On a cool day, or under any circumstances where a smaller supply is desirable in the reservoir C, 120 the float L may be lowered to any point by adjusting the set nut on the supporting rod, this arrangement permitting the adapting of the apparatus to a large or small volume of vending.

What I claim as my invention is:

1. A liquid dispensing apparatus comprising an outer casing, an inner casing supported on the bottom of the outer casing and separated from the body portion of the outer 130

casing by a closed air space surrounding said inner casing, a still liquid reservoir supported in the upper portion of the inner casing and separated from the sides of the inner casing 5 by a space for the storage of ice and from the bottom of said inner casing by a space providing a chamber communicating with the ice space, a conduit leading from a charged liquid supply and entering said chamber, the 10 said conduit being elongated and coiled within said chamber and having branches within said chamber, one branch entering the still liquid reservoir and the other extending as a charged liquid outlet through 15 the walls of the inner and outer casings, means for controlling the branch entering the reservoir, a still liquid outlet extending from the reservoir through the walls of the casings and across the space between them 20 and means outside the casing for controlling said liquid outlets.

2. A liquid dispensing apparatus comprising an outer casing, an inner casing supported on the bottom of the outer casing and 25 separated from the body portion of the outer casing by a closed air space surrounding said inner casing, a still liquid reservoir supported in the upper portion of the inner casing and separated from the sides of the inner casing 30 by a space for the storage of ice and from the bottom of said inner casing by a space providing a chamber communicating with the ice space, a conduit leading from a charged liquid supply and entering said chamber, the 35 said conduit being elongated and coiled within said chamber and having branches within said chamber, one branch entering the still liquid reservoir and the other extending as a charged liquid outlet through 40 the walls of the inner and outer casings, a float valve within said reservoir controlling the outlet of the branch into the reservoir, a still liquid outlet extending from the reservoir through the walls of the casings and 45 across the space between them and means outside the casing for controlling said liquid outlets.

3. A liquid dispensing apparatus comprising an outer casing, an inner casing supported on the bottom of the outer casing and 50 separated from the body portion of the outer casing by a closed air space surrounding said inner casing, a still liquid reservoir supported in the upper portion of the inner cas-

ing and separated from the sides of the inner 55 casing by a space for the storage of ice and from the bottom of said inner casing by a space providing a chamber communicating with the ice space, a conduit leading from a charged liquid supply and entering said 60 chamber, the said conduit being elongated and coiled within said chamber and having branches within said chamber, one branch entering the still liquid reservoir and the other extending as a charged liquid outlet 65 through the walls of the inner and outer casings, means for controlling the branch entering the reservoir, a still liquid outlet extending from the reservoir through the walls of the casings and across the space between them and a double draft faucet outside said chambers for controlling both of 70 said outlets.

4. A liquid dispensing apparatus comprising 75 an outer casing, an inner casing provided with a supplementary bottom elevated from the bottom of said outer casing and forming a cold storage chamber, a settling tank containing liquid in a still or settled condition within said cold storage chamber, a coil resting upon the supplementary bottom of said chamber, pipes connecting said coil to charged-liquid supply and to said settling tank, a pressure regulating valve in the pipe connecting the refrigerating coil and the 80 charged-liquid supply, a float valve located within the settling tank governing the flow of liquid from the source of supply to the settling tank, an overflow pipe for the 85 iced water extending through the outer casing and having its entrance port located near the upper level of the liquid in the settling tank, a double draft dispensing faucet secured to the outer and inner casings, a pipe connecting 90 said faucet to the bottom of said settling tank through which the liquid is drawn off by gravity in a still condition, and a smaller pipe connecting said faucet to the pipe leading from the source of charged-liquid supply 95 through which liquid under pressure is drawn from said charged liquid supply.

Signed at New York in the county of New York and State of New York this 26th day of May A. D. 1906.

HARRY S. CORNISH.
